SUCTION CLEANER

Edward R. Swann, North Canton, Ohio, assignor to The Hoover Company, North Canton, Ohio, a corporation of Ohio

Application June 25, 1958, Serial No. 51,525

Term of patent 14 years

(Cl. D9—2)

The characteristic features of the design for the suction cleaner disclosed reside in the handle and base member having the configurations shown.

I claim:

The ornamental design for a suction cleaner, substantially as shown and described.
